UNITED STATES PATENT OFFICE

127,762

DESIGN FOR AN EMBROIDERED LACE TRIMMING OR SIMILAR ARTICLE

Otto Hallbauer, West Englewood, N. J., assignor to Stein-Tobler Co. Inc., Union City, N. J., a corporation of New Jersey

Application May 8, 1941, Serial No. 100,842

Term of patent 3½ years

To whom it may concern:

Be it known that I, Otto Hallbauer, a citizen of the United States, residing at West Englewood, Bergen County, and State of New Jersey, have invented a new, original, and ornamental Design for an Embroidered Lace Trimming or Similar Article, of which the following is a specification, reference being had to the accompanying drawing, forming part thereof, wherein the figure is a plan view of an embroidered lace trimming or similar article, showing my new design.

I claim:

The ornamental design for an embroidered lace trimming or similar article, substantially as shown.

OTTO HALLBAUER.
